PERFORATING MACHINE

James W. Bryce, Bloomfield, N. J., assignor, by
mesne assignments, to International Business
Machines Corporation, New York, N. Y., a cor-
poration of New York

Application August 2, 1929, Serial No. 383,046

4 Claims. (CL. 164—115)

This case is concerned with a novel perforator for record cards or sheets used as control elements of automatic accounting machines.

To perforate a card with index points corresponding to original data, usually in the form of conventionally readable characters, it has been necessary for the operator to read the original data and manually control a perforator in accordance with the data. This procedure requires a skilled operator to assure efficient and speedy operation of the perforating machine. Further, even with a skilled operator, there is still the possibility of error due to human fallibility.

It is obviously advantageous to eliminate the human factor in perforating a card with original data. The elimination of the human factor would save the cost of skilled labor, reduce the possibilities of error, and enable speedier as well as more accurate transcription of the original data into the form of index points on record cards.

Broadly, therefore, the object of the present invention is to eliminate the human factor in perforating a card with data.

Stated more specifically, the object of the invention is to automatically control a perforator by means of original data for perforating a card with index points or perforations designating said data.

Further, an object of this invention is to automatically read graphic or printed or written characters of a record sheet and perforate a tabulating card in accordance with the characters.

Still further, an object of this invention is to sense conventionally readable printed or written data and perforate a card in accordance therewith.

A further object of the invention is to read original data one item at a time and thereby control a perforating device in accordance with the items.

Again, an object of the invention is to read the original data one item at a time and control the perforator for step by step operation in accordance with said items.

An object is also to read original data and automatically control a perforator in accordance therewith to punch a card with no more than a single index point in each column.

A further object is to provide alternative means for reading original or graphic or conventional characters to control a perforator for punching a card with combinational hole index points corresponding to the data.

Still further, an object of the invention is to automatically read printed or written data from

a sheet and electrically control punch-operating devices in accordance with said data.

Another object of the invention is to read data either in printed or written form or in the form of index points by means of light analyzing devices to electrically control a perforator.

Further and other objects and advantages will be hereinafter set forth in the accompanying specification and claims, and shown in the drawings, which by way of illustration show what is now considered to be the preferred embodiment of the invention.

In the drawings:

Fig. 1 is a front view of the right half of the carrier and feeding mechanism for the sheet containing the printed or written matter.

Fig. 2 is a section on line 2—2 of Fig. 1.

Fig. 3 is a longitudinal sectional view of the punching mechanism.

Fig. 4 shows the arrangement of the written or printed numerals 0-9 with respect to the code points of which the analysis is taken.

Fig. 5 shows a single control field of the printed sheet with the arrangement of code points.

Fig. 6 is a table of the combination of code points characterizing each of numerals 0-9.

Fig. 7 is a detail of Fig. 1.

Fig. 8 is a circuit diagram of the machine arranged for punching a card in accordance with a single index point code.

Fig. 9 is a plan view of a part of the punch shown in Fig. 3, and,

Fig. 10 is a circuit diagram of an embodiment of the invention designed for perforating a card in accordance with a combinational hole code.

In general, the invention is embodied in a machine having a control section and a punching section. The former section includes the control sheet containing original printed or written items and a light analyzing device for reading the items one by one and controlling the punching section to perforate a card with index points corresponding to the analyzed items. The control of the punching section is effected by the analyzing device through the selective operation of a plurality of circuits, which selectively energize magnets for causing operation of the punches.

Referring to the drawings in detail, Figs. 1 and 2 illustrate the control section of the machine. This section comprises a fixed frame 10 provided with vertical bars 11, 12, and 13 disposed lengthwise of the frame.

Bars 11, 12, and 13 serve to slidably support

the carriage 15 for movement longitudinally of the fixed frame. Bar 11 is provided for this purpose with upper and lower vertical rollers 16 between which is disposed the forward end of a bar 17 rigid with the carriage and extending lengthwise of the carriage. The rear end of bar 17 is engaged by horizontal rollers 18 carried on the upper end of bar 12. Rigid with the rear of carriage 15 are a pair of longitudinally extending rails 19 between which are seated rollers 20 carried by bar 13. To further guide carriage 15 for slidable movement on the fixed frame, the latter carries a longitudinally disposed rod 21 passing through an opening 22 in the carriage.

The side plates 25 of the carriage rotatably carry a cylindrical platen 26 having fixed to the ends thereof wheels 27 provided with rounded notches 28 on the periphery. A holding pawl 29 pivoted to the side plate 25 adjacent the notched wheel is urged by a spring 30 into engagement with the periphery of the wheel. The pawl restrains accidental rotation of platen 26 but will freely ride out of the notches 28 upon the platen being rotated by a knob 31 fixed to the end of the shaft 32 of the platen.

The platen is adapted to support on its periphery the opaque control sheet S bearing rows of items printed thereon in any color contrast-30 ing with the color of the sheet. The rear of the sheet S rests on inclined plate 35 rigid with the carriage. The sheet then passes around the periphery of platen 26 and upwardly into engagement with the front of a vertical plate 36

35 rigid with the carriage.

The control sheet is held in firm engagement with the periphery of platen 26 by rollers 37 and 38. Rollers 37 are rotatably carried between the upper ends of plates 39. The lower ends 40 of said plates are rotatably mounted on a shaft 40 mounted in the carriage. Springs 41 are coiled about the shaft 40 and have one of their ends fixed to the shaft. The other of their ends is fixed to the plates 39. The effect of the spring 45 is to normally move rollers 37 towards the platen 26.

Rollers 38 are journaled in plates 43 which are also rotatably carried by shaft 40 and urged towards the platen by springs 44. A rod 45 limits the movement of plates 39 and 43 towards the platen.

The rod 45 is of oblong shape and is journaled at its ends between the side plates 25. The rod has at one end a knob handle 46. When the long sides of rod 45 are in contact with the plates 39 and 43, they permit the rollers to engage the platen. By turning the knob 46, the short sides of rod 45 may be made to contact with the plates 39 and 43 thereby moving the rollers 37 and 38 away from the platen and permitting a control sheet to be inserted between the said rollers and the platen.

Rollers 47 mounted on a rod 48 carried by the side plates 25 press the control sheet firmly into engagement with the vertical plate 36.

65 A spring drum motor 50 is carried by the fixed frame 10 and is connected to the carriage 15 to move it longitudinally of the frame. An escapement mechanism is provided to cause the carriage to move one step at a time under the influence of motor 50. The escapement mechanism includes a rack 52 attached to the bottom of the carriage bar 17 and a pair of pivoted pawls 53 and 54 for alternately engaging the rack teeth.

Pawl 53 has a notch 55 engaged by a pin 56 carried by one end of a lever 57. The other end of lever 57 carries a pin 58 loosely seated in a hole 59 in the pawl 54. The lever 57 is fixed intermediate its ends to a rod 60 on which is also loosely pivoted the pawl 54 by means of an elongated slot 61. The reason for an elongated slot 61 and the loose connection between pin 58 and hole 59 of pawl 54 is to permit longitudinal movement of the pawl under the influence of a spring 62.

As shown in Fig. 2, the pawl 54 is in engagement with rack 52 and pawl 53 is out of engagement therewith. By rocking lever 57 clockwise, as viewed in Fig. 1, pin 56 coacts with slot 55 to force the nose of pawl 53 into engagement with the rack teeth. At the same time, pin 58 and slot 59 coact to force the nose of pawl 54 downwardly and out of contact with the rack teeth. As soon as the pawl 54 disengages a tooth of rack 52, spring 62 pulls it forward under the edge of the next tooth, the rack being held stationary by pawl 53. When the lever 57 is rocked counterclockwise back to the position shown in Fig. 1 the pawl 53 is disengaged from the rack and pawl 54 moved upwardly. The nose of pawl 54 has however been moved forward by spring 62 so that when the lever 57 now rocks pawl 54 upwardly, it engages the next tooth. Pawl 53 now being disengaged from the rack, spring motor 50 actuates the rack 30 to the left for one tooth space when pawl 54 moving with the rack reaches the limit of its left hand position and is stopped by pins 58 and 60, thus stopping the rack.

Lever 57 which controls the pawls 53 and 54 in the manner just described is actuated by the armature 65 of a magnet 66 supported by the fixed frame. The magnet is energized by means hereinafter described in detail. A spring 67 normally rocks the armature counterclockwise on its pivot 68 as viewed in Fig. 1 and away from the magnet. A stud 69 is provided to engage and limit this movement of the armature.

To analyze the printed characters P of the control sheet, an analyzing beam of light 75 is projected from a source 76 in a downwardly inclined direction upon a lens 77. The lens directs the rays of the beam in parallel paths upon a portion of the control sheet resting against the vertical plate 36. The analyzing beam having hit the control sheet at an angle is reflected therefrom to a diverging lens 78. The latter casts an enlarged image of the beam on a glass plate 79.

Directly below and in proximity to the glass plate 79 is a housing 80 in which are four photoelectric cells A, B, C, and D. The function of the plate 79 is to accurately and conveniently position the beam with relation to the photo-electric cells. The photo-electric cell is extremely reactive to light and if placed in series in a circuit will vary the current in the circuit in proportion to the intensity of the light acting on the cell.

Referring to the circuit diagram, Fig. 8, a source of electric energy, as battery 85, is placed in series with each of the photo-electric cells. Now, if cell A, for example, is in the path of light rays directed through plate 79 (Fig. 2), it will be energized and a circuit will be completed from one side of the battery 85 through the manual switch 86, line 87, cell A, and an amplifying unit 88, through a switch 89, to the other side of the battery. The amplifying unit is preferably of the vacuum tube type, and will send a greatly amplified current through a magnet coil 90.

In a similar manner when cells B, C, and D are energized by light, circuits will be completed respectively through amplifiers 91, 92, 93 and magnet coils 94, 95 and 96.

5 Respectively coacting with magnets 90, 94, 95, and 96, are armatures 97, 98, 99, and 100.

In the embodiment of the invention designed to perforate the cards in accordance with a single index point code, each point representing a different character, armature 97 is connected by a link 101 to a selecting contact blade 102 cooperating with either upper contact 103 or lower contact 104. Armature 98 is connected by a link 105 to a plurality of selecting contact blades 106, each of which may cooperate with one or more contact points. Similarly, armatures 99 and 100 are respectively connected to a plurality of selecting contact blades 107 and 108, each of which cooperates with one or more contacts. The contacts cooperate in series in combinations to close circuits through punch selector magnets M-0 to 9, only one magnet at a time being energized.

Thus, if photo cell C is energized by light, armature 99 will be attracted to move contact blades 107 into engagement with upper contact points 109. A circuit will then be completed as follows: from the plus side of the power source through manual switch 110, contacts 111, blade 102, lower contact 104, blade 107, upper contact 109, blade 106, contact 112, blade 108, contact 113, line 114, punch control magnet M-8, and through line 115 to the minus side of the power source. The punch magnet M-8 upon energization causes perforation of an index point in the eight position of a column of the record card in the punching section in a manner which will be explained hereinafter in detail.

To further illustrate the operation of the photo cells in selecting a punch magnet for energization, assume cells A, C and D are acted on by light, energizing each of these cells. This will cause actuation of armatures 97, 99, and 100 to raise blades 102, 107, and 108, respectively. A circuit will now be completed from the plus side of the power source through switch 110, contacts 111, blade 102, contact 103, blade 107, contact 109, blade 106, contact 116, uppermost blade 108, contact 117, line 118 and through punch magnet 5 and line 115 to the minus side of the power source. Punch magnet 5 being energized will cause a perforation to be made in the five position of a column of the card in the punching section in a manner which will be explained in detail hereinafter.

5 In a similar manner, each of punch magnets M is designed to be energized to cause a single punch to operate upon energization of a combination of the photo cells A, B, C, and D. Fig. 6 shows the code employed in the present instance. The dark circles represent inactive cells and the blank circles represent energized cells. Different combinations of blank and dark circles correspond to the punch marks in the card for representing the numbers 0 to 9. It is obvious that other combinations of dark and energized cells than those shown and described may be used. It is also obvious that the combinations are not restricted to causing punching of only numbers but may control punches for perforating a card with index points representing other characters, as for example, letters of the alphabet.

Fig. 5 illustrates a single control field or portion of the control sheet containing a single control character P (see Fig. 1). Control points 120—A, B, C, and D are selected on the control field to be

in the same relation to analyzing beam 75 as the photo cells A, B, C, and D are to the beam when it is spread out by lens 78 on plate 79. Thus if control point A is struck by rays of the beam 75 reflects these rays to plate 79, photo cell A 5 will be in the path of these rays and consequently be energized. In the same way, when B, C, or D reflect light rays, the corresponding cells B, C or D will be energized. On the other hand, if instead of reflecting rays, either of control points 10 A, B, C, or D absorbs the rays, their corresponding photo cells will not be energized. It is well known that a black surface absorbs light and that a white surface reflects light. Hence by selectively making points A, B, C, or D black, they 15 will absorb rays of the analyzing beam 75 and their corresponding cells will be inactive.

Referring to Fig. 4, the manner in which points A, B, C, or D are selectively made black will be understood. If the control sheet is white, a black 20 character thereon will absorb light rays. Thus the black character 1 is placed in the control field so as to cover points B and C leaving points A and D exposed; number 8 covers points A, B, and D, leaving C exposed; and in a similar manner each of characters 0-9 on the control sheet 25 is contained in a single control field and selectively covers and exposes the combination of points indicated in Fig. 4 and in tabular form in Fig. 6.

30 Referring to Figs. 1 and 2, it will now be clear that when the analyzing beam strikes character 8, for example, the control points A, B, and D being covered will not reflect the beam and corresponding cells A, B, and D will be inactive. 35 Control point C being exposed will reflect rays of the beam to plate 79 and the cell C will be energized to cause energization of punch-operating magnet 8 in the manner previously explained herein.

40 The analyzing beam 75 is of the same dimension as a single control field. Hence the beam will read one character at a time. The carriage 15 (Figs. 1 and 2) is moved longitudinally of the fixed frame 10 the distance of one control field 45 after a character has been analyzed and a punch-magnet energized to cause operation of a punch corresponding to the analyzed character. This movement of the carriage is accomplished upon energization and deenergization of magnet 66 50 through the escapement mechanism previously described herein. After a complete row of characters has been analyzed the knob 31 is turned to rotate platen 26 and feed a second row of characters into cooperation with the analyzing 55 device. The pawl 29 and wheel 27 coact to hold the platen and control sheet in adjusted position.

The manner in which the punch-actuating magnets M upon their being energized cause operation of the punches will be made clear with 60 reference to Fig. 3. A column of punches 125 are vertically, slidably, mounted in the frame 126. Each punch is above an index point position of a single column of the Hollerith record card 127 when the latter is at rest on the bed 128 of the 65 frame.

Resting on the head of each punch is an interposer bar 129. The bar has a notch 130 at its forward end which is normally underneath hammer 131 and permits the hammer to freely move 70 downwardly without effecting corresponding movement of the bar. If the bar is moved forward, however, the hammer 131 will be above the top edge of bar 129 and downward movement of the hammer will result in actuation of the bar down- 75

wardly thereby forcing the coacting punch 125 downwardly to perforate the card 127. Bar 129 may be moved forward by rocking lever 132 counterclockwise, as viewed in Fig. 3. This may be done by manually depressing keys 133 or by magnet M being energized to attract armature 134 comprising the right hand end of lever 132.

Lever 132 when rocked counterclockwise acts upon a vertically slideable rod 135 to move the latter downwardly. The latter in turn rocks a bell lever 136 counterclockwise against the influence of spring 137. The upper end of bell lever 136 is pivoted to interposer bar 129 and when rocked counterclockwise slides the latter forwardly on frame ledge 138 to position it for coaction with hammer 131. The interposer bar is provided with a shoulder 139 engaging the side of a pivoted bar 140 extending across the machine. When the interposer moves forward shoulder 139 rocks bar 140 counterclockwise against the force of spring 141. One end of the bar during such movement engages a shoulder 142 on the forward end of a rod 143 to move the rod forwardly. The rear end of the rod is attached to a spring blade 144 and moves the blade and a contact point 145 thereon into engagement with a fixed contact point 146. As a result, a circuit is completed, referring to Fig. 8, from the plus side through contacts 145-146, through the common hammer actuating magnet 147, and escapement magnet 66 to the minus side of the line.

Referring to Fig. 3 the magnet 147 when thus energized attracts armature 148 which through links 149 and 150 rocks the hammer 131 counterclockwise thereby forcing interposer bar 129 which is now in its forward position downwardly to effect operation of punch 125 against the influence of spring 151. When hammer 131 rocks counterclockwise a tail 152 thereon engages a hook 153 rigid with rod 143 and lifts the shoulder 142 against the resistance of spring 154 into line with a slot 155 in the rod 140 thereby permitting spring blade 144 to move contact 145 away from contact 146. The circuit through magnet 147 is thus opened.

Near the completion of the punching operation, it is necessary to break the circuit through the selector magnets M. This is effected by a projection 158 (see Fig. 3) on link 149 forcing a spring blade 159 and a lug 160 thereon downwardly. The lug 160 engages a spring blade 161 and opens contacts 111 (see Fig. 8) thereby breaking the circuit through the magnets M.

Armatures 97, 98, 99 and 100 when attracted by their corresponding magnets are latched in position by pivoted latches 163. At the completion of the punching operation, the armatures must be released for a subsequent operation. This is effected by closing of contacts 164 (Figs. 3 and 8) when plate 159 is depressed, simultaneously with opening of contacts 111. Referring to Fig. 8 it is seen that closing of contacts 164 closes a circuit through a magnet 165 which thereupon attracts its armature 166 to move a rod 167 to the right which through lugs 168 cooperating with pins 169 on the latches releases the latches from the armatures 97, 98, 99 and 100 permitting the latter to drop to initial position.

When contacts 111 are opened in the manner explained above, the selected magnet M is deenergized and permits lever 132 to rise. Spring 137 thereupon acts through ball 136 to move the interposer 129 to initial position. After contacts

111 have been opened and contacts 164 closed contacts 145 and 146 break, as explained previously, to deenergize magnet 147. The lug 158 thereupon releases plate 159 and permits contacts 111 to close and contacts 164 to open. Opening of the latter contacts deenergizes magnet 165 and releases latches 163 for cooperation with armatures 97, 98, 99, and 100.

Since contacts 111 are now closed and the armatures 97 to 100 in readiness for latching, if the control sheet remained stationary, the same magnet M would again be energized to cause punching. As explained previously, however, the control sheet is automatically advanced one step after each punching operation. This advance is effected upon deenergization of magnet 66 which as may be seen from Fig. 8 occurs simultaneously with deenergization of magnet 147 by opening of contacts 145 and 146 upon completion of the punching operation. When magnet 66 is deenergized, lever 57 (see Fig. 1) rocks counterclockwise, releasing pawl 53 from escapement rack 52 and permitting the latter to move with the carriage 15 one tooth space before it is stopped by pawl 54.

While the record sheet is moving from one position to the next and the beam of light is passing over the space between two adjacent characters, it would be possible, if no means were provided to prevent it, for the photo cells to be prematurely energized thereby latching one or more of the armatures 97 to 100 which armatures might remain latched when the next character is being sensed thereby causing an erroneous analysis. Further, if the action of pawls 53 and 54 under control of magnet 66 is faster than the action of the tail 158 (see Fig. 3) in deenergizing magnet 165 under the control of magnet 147, the control sheet carriage will move while the latches 163 are still in ineffective position. Undesirable energization of the cells might then occur as explained above to attract the corresponding armatures momentarily. The latches being ineffective, the armatures will simply flutter from attracted to released positions.

Both undesirable latching of the armatures 97 to 100 and fluttering of the armatures by energization of the cells while the control sheet is in motion is prevented by opening of contacts 89 (see Figs. 7 and 8) under control of pawl 54 (Fig. 50 1) as soon as magnet 66 is energized under control of the selected magnet M. The opening of contacts 89 is thereby effected while magnet 66 is energized at which time the control sheet is stationary. Contacts 89 remain open to prevent completion of a circuit through the photo cells until the punching operation has been completed and the control carriage moved to the next position.

Referring to Figs. 1 and 7, contacts 89 are seen to be normally held closed by engagement of the contact blade 175 with the rear end of pawl 54 while the latter is holding rack 52 stationary. When magnet 66 is energized under control of a magnet M, the pawl 54 is released from the rack. As previously described, spring 62 thereupon immediately draws the pawl to the right as viewed in Figs. 1 and 7. The rear end of pawl 54 thereby moves away from blade 175 the length of slot 61 and the contacts 89 open. Rack 52 is now being held stationary by pawl 53. When the punching operation is completed, magnet 66 is deenergized to withdraw pawl 53 from the rack and the latter moves to its new position. Pawl 54 thereupon is moved by rack 52 to its initial position.

position—see Figs. 1 and 7—and reaches said position simultaneously with completion of the movement of the rack. The contacts 89 therefore remain open until the rack is again at rest, 5 after which they stay closed until magnet 66 is again energized.

After a card 121 in the punching section is perforated, the card is advanced to the next column for the succeeding punching operation. To 10 accomplish this, the card feeder 180 (Fig. 3) is provided with a rack 181 moved through gears 182 by a spring drum 183. The rack is normally prevented from moving by engagement with pawl 184. During punching when actuator 131 de- 15 presses an interposer 129, a bail 185 is rocked by the latter counterclockwise (Fig. 3). Lever 186 rigid with bail 185 thereupon moves pawl 184 out of engagement with rack 181 and moves a pawl 187 into engagement with the rack preventing movement of the latter. Spring 187a 20 moves pawl 184 to the right (Fig. 3) to the limit of slot 188 to position the pawl above the next tooth of rack 181.

When the punching operation is completed, interposer 129 permits bail 186 to rock clockwise, 25 releasing pawl 187 from the rack and permitting the latter to move one tooth space to the left before stopped by pawl 184. In this manner a punching operation is finished, the next card column is fed under the punches. This feeding movement occurs when the interposer is released by actuator 131 as soon as magnets 66 and 147 are deenergized. The magnet 66 effects feeding of the control sheet. Thus the card in the 30 punching section and the control sheet are simultaneously fed step by step.

The operation of the machine shown in Figs. 1 to 9, in brief, is as follows:

The control sheet is at rest, contacts 89 and 40 111 are closed and contacts 145—146 and 164 are open. Analyzing beam 75 is reading control character 4, for example, on the control sheet. The control character 4 reflects the analyzing beam onto plate 79 and the reflected beam is 45 dark in the C and D positions (see Figs. 4 and 6). Cells A and B alone are therefore energized by light and corresponding armatures 97 and 98 are attracted by magnets 88 and 91, respectively. The armatures are latched in attracted position 50 by latches 163. A circuit (see Fig. 8) is now complete from the plus side of the power through switch 110, contacts 111, blade 102, contact 103, blade 107, blade 106, contact 190, blade 108, contact 191, line 192 and through magnet M—4 to 55 the minus side of the power. The magnet M—4 thereupon through the lever 132 corresponding to the punch in four position of the card column causes the interposer 129 of the "four" punch to advance. Contacts 145 and 146 are thereby 60 closed by rod 143 energizing magnets 66 and 147 (see Figs. 3 and 8).

Magnet 66 thereupon disengages pawl 54 from the rack and opens contacts 89 preventing further energization of the photo cells until the 65 next cycle.

Magnet 147 upon energization, operates actuator 131 which through interposer 129 depresses the punch 125. Tail 158 controlled by magnet 147 has, then moved in position to open contacts 111 deenergizing magnet M—4 and permitting the interposer to return to initial position.

When contacts 111 are opened, contacts 164 are closed to release latches 163 from armatures 97 and 98.

Immediately after opening of contacts 111 and

closing of contacts 164, the tail 152 of actuator 131 releases rod 143 from plate 140 and permits contacts 145 and 146 to open. This deenergizes the magnets 147 and 66. The former then causes contacts 111 to close and contacts 164 to open at 5 the same time permitting the actuator 131 to rise and cause operation of the escapement 181 to feed the card a column space.

Coincidentally, deenergization of magnet 66 causes the control sheet to be fed through release 10 of escapement of rack 52. At the completion of the escapement movement, pawl 54 closes contacts 89. The control sheet is now at rest in a new position, contacts 89 and 111 are closed, contacts 145—146 and 164 are open. This is the 15 initial status of the machine and a new cycle is ready to begin.

In automatic accounting practice, a combinational hole system of representing characters is made use of in addition to or as an alternative 20 to the Hollerith or single point system of representing characters. The combinational hole system permits use of a smaller card space for representing a greater number of characters and is especially designed and adapted to represent letters of the alphabet. 25

When using the combinational hole system, the tabulating card is perforated with a combination of holes, each combination representing a different character.

Fig. 10 illustrates a modification of the invention whereby combinational hole punching of a card under control of the original data on sheet S is accomplished. In place of armatures 97, 98, 99, and 100 each controlling a plurality of contacts acting in combinations to cause a single punch at a time to operate as explained in connection with Fig. 8, each of said armatures controls only a single contact which by itself causes a punch to operate. Energization of a plurality 40 of cells will therefore cause simultaneous operation of a plurality of punches. 30

The control field of a combinational card in the present instance, is similar in appearance to the table in Fig. 6 and each card may have a plurality of such fields one above the other. Thus, if in one column a perforation occurs in each of card positions A and D, the column designates number 1. If the next column has perforations in the A, C, and D positions, it represents number 5 50 5, and so on.

It is clear that Fig. 6 represents not only the control field of a card and the combinations of perforations for designating different characters but also represents the cell combinations energized by reading of the same characters. Thus, if character 3 on control sheet S is sensed by beam 75, cells C and D are energized and cause operation of the punches to perforate positions C and D of the combinational card to designate 60 character 3.

In more detail, referring to Figs. 1, 2, 3, 6 and 9, assume that analyzing beam 75 is reading character 7 on the control sheet S, the carriage 15 is at rest, contacts 89 and 111 are closed, and contacts 145—146 and 164 are open. By reference to Fig. 6, it is seen that analysis of character 7 energizes cells A, B, and D. Energization of these cells causes magnets 90, 94, and 96 to attract the corresponding armatures 97, 98, and 100 which are then latched by members 163. Armatures 97, 98, and 100 upon attraction, move contact fingers 200, 201, and 203 into engagement with contacts 204, 205 and 207. Circuits are thereby simultaneously completed through each of magnets 75

- M—A, M—B, and M—D, the path of the circuits being from the plus side of the line through switch 111, common line 208, and through the closed contacts 200—204, 201—205, and 203—207 5 through magnets M—A, M—B, and M—D respectively to the common return line 209. Energization of the magnets M—A, B, and D, operates the corresponding levers 132 to advance the interposers 129 above the A, B, and D positions of the 10 card as indicated in Fig. 9. The interposers thereupon through members 140 and 143 (see Fig. 3) close contacts 145—146 (see Figs. 3, 9 and 10). This completes a circuit through magnets 147 and 66 (see Fig. 10). Magnet 147 thereupon operates 15 hammer 131 to depress the advanced interposers and operates the corresponding punches in the A, B, and D positions of the card.

The remaining operation of the machine is the same as that of the first-described single-hole embodiment of the invention. Thus, magnet 66 20 operates the escapement of carriage 15 to advance the control sheet to the next number, magnet 165 is energized to withdraw the latches 163 from the attracted armatures, the punch carriage is advanced and a new operation is ready to begin.

In a similar manner, energization of any combination of magnets M—A, B, C, and D causes combination punching of the tabulating card to represent the numbers 0-9 in accordance with 30 the code shown in Fig. 6.

It is apparent that while the invention has been shown as applied to the modifications disclosed herein, variations within the limits permitted by the functions and relations necessary to 35 the proper carrying out of the principles of the invention may be made by those skilled in the art without departing from the spirit of the invention. It is intended to be limited therefore, only by the scope of the following claims:

- 40 1. A machine for making a perforated record comprising a column of punches, a control sheet bearing data designated by conventionally significant characters such as printed numerals, each in a separate field of the sheet and each spread 45 over and covering one or more points arbitrarily arranged vertically and horizontally in the field relative to each other, a plurality of light reactive elements, equal in number to the points in said field, for simultaneously reading all the points 50 of a field at one time, means for selecting the punches by the light reactive elements in accordance with the combination of points in each field read thereby, means for operating the selected punches to make a record corresponding in value 55 to the conventionally significant characters read by the light reactive means, and separate means

for feeding the perforated record and control sheet in response to each operation of the punches.

2. A machine for making a perforated record, comprising a series of punches, a control sheet bearing data designated by conventionally significant characters such as numerals, each character being in a separate field and spread over and covering one or more of a series of arbitrarily arranged points in the field, a plurality of light sensitive elements for successively reading each 10 character and operated in combinations depending on the combinations of points in a field covered by the character therein, means controlled by a combination of said elements for operating only one of the punches to make a perforated 15 record corresponding to the value of the conventionally significant character read by said elements, and separate means for feeding the perforated record a distance equal to the distance between the successive perforations and the control sheet a distance equal to the distance between successive characters.

3. A machine for making perforated records comprising a reading device for analyzing printed characters and including a bank of sensing elements adapted to be combinationaly selectively activated by uncovered portions of the background or field of a data sheet on which the characters appear, perforating devices, selecting mechanism controlled by the sensing elements for setting one 30 or more of the perforating devices according to portions of the background which are not covered by the character, and separate means for controlling the position of the data sheet and the records being perforated by the perforating devices. 35

4. In combination, a control sheet bearing data designations in the form of visual characters of conventional shape such as numerals, a plurality of sensing points, a plurality of analyzing elements, equal in number to the said points, for 40 interpreting the visual significance of the characters including devices for reading limited fields of the control sheet each of which fields contains a character and said analyzing elements being adapted to be simultaneously and combinationaly 45 affected differently by different characters, record perforating devices controlled by the analyzing elements in accordance with the combination of analyzing elements affected by a character sensed by said elements, and separate means for 50 causing the analyzing means to successively analyze different fields of the control sheet and for causing the record to be perforated in successive different places by the perforating devices.

JAMES W. BRYCE.
